(57) **CLAIM**

The ornamental design for a throwing apparatus, as shown and described.

DESCRIPTION

FIG. 1 is a perspective view showing an exemplary embodiment of our new throwing apparatus design;

FIG. 2 is a top view thereof;

FIG. 3 is a bottom view thereof;

FIG. 4 is a left side view thereof;

FIG. 5 is a right side view thereof;

FIG. 6 is a front view thereof;

FIG. 7 is a back view thereof;

FIG. 8 is a perspective view showing an alternative exemplary embodiment of our new throwing apparatus design;

FIG. 9 is a top view thereof;

FIG. 10 is a bottom view thereof;

FIG. 11 is a left side view thereof;

FIG. 12 is a right side view thereof;

FIG. 13 is a front view thereof; and,

FIG. 14 is a back view thereof.

It should be noted that, pursuant to 37 C.F.R. § 1.152 and MPEP § 1503.02, Part III, broken lines have been used in the drawings to illustrate inherent but unclaimed features of our Throwing Apparatus design, which features are expressly not claimed as part of said design, are shown strictly for context, and are unrelated to any indication of the relative importance of such features.
